CLAIM

The ornamental design for a wine rack, substantially as
shown and described.

DESCRIPTION

FIG. 1 is a perspective view of a wine rack showing my
new design;

FIG. 2 is a top plan view, the bottom view being identi-
cal thereto;

FIG. 3 is a front elevational view, the rear view being
identical thereto; and

FIG. 4 is a left side elevational view, the right side being
identical thereto.

FIG. 1

FIG. 4

FIG. 2

FIG. 3
